DESIGN FOR A DISPLAY STAND

Harry Stuart Johnston, Jr., Milwaukee, Wis., assignor to The Robert A. Johnston Company, Milwaukee, Wis., a corporation of Wisconsin

Application November 1, 1937, Serial No. 72,558

Term of patent 7 years

To all whom it may concern:

Be it known that I, Harry Stuart Johnston, Jr., a citizen of the United States, residing at Milwaukee, in the county of Milwaukee and State of Wisconsin, have invented a new, original, and ornamental Design for a Display Stand, of which the following is a specification, reference being had to the accompanying drawing, forming part thereof.

Both sides of the design have the same appearance.

I claim:

The ornamental design for a display stand, as shown and described.

HARRY STUART JOHNSTON, Jr.
